CABLE LOOPING PLIERS

John Kohler, Akron, Ohio, assignor of one-half
to Arthur S. Helbig, Akron, Ohio

Application April 3, 1952, Serial No. 280,270

2 Claims. (Cl. 81—15)

1

The invention relates to a hand tool for bending a wire cable and more particularly to an improved tool of the pliers type for bending the cable into a substantially closed loop and holding the loop while a retaining clip is secured to the ends thereof.

In the use of wire cables for many purposes, e. g., as guy wires, it is frequently necessary to bend the attaching end of the wire into a loop and to secure the free end to the run of the cable by means of a suitable clip. Certain prior tools for bending wires or cables have had various disadvantages. For example, such tools have lacked the proper elements to bend the cable easily into a regular loop, or have not had means to secure the handles in loop-forming position. Also, such tools have not been designed to make a relatively sharp bend in the wire.

Moreover, all of the prior tools for this purpose of which I am aware, have been cumbersome, awkward and unwieldy in operation.

It is an object of the present invention to provide an improved tool for bending by hand a wire cable into a relatively small substantially closed regular loop.

Another object is to provide an improved wire loop bending tool which is designed to produce efficient lever action during the bending operation.

A further object is to provide a simple and inexpensive tool which accomplishes the foregoing desiderata.

These and other objects are accomplished by the parts, combinations and constructions comprising the present invention, a preferred embodiment of which is shown by way of example in the accompanying drawing and described in detail in the specification, the scope of the invention being defined in the appended claims.

Referring to the drawings forming part hereof,

Fig. 1 is an elevation of the improved tool with the jaws in closed position for forming a loop indicated in dot-dash lines;

Fig. 2 is a side view, partly in section, taken on line 2—2, Fig. 1;

Fig. 3 is a fragmentary elevation showing the jaws in open position at the start of forming the loop; and

Fig. 4 is an elevation of one of the cable-engaging hooks which are mounted on the ends of the jaws.

The handle levers are indicated at 5 and 6 and are pivotally connected or hinged together by a pivot pin 7 passing through their crossed portions. The levers 5 and 6 may be made of

flat bar stock and are preferably offset at 8 and 9, respectively, towards each other to bring the lower handle portions 10 and 11 substantially in the same plane and to limit the closing movement of the levers by abutment of the offset portions.

One of the handle portions, shown in the drawing as the portion 11, has one end of a wire loop 12 passing through its lower end, the free end of said loop being adapted to swing over the end of the other handle portion 10 when the handles are in closed position as shown in Fig. 1. Thus the loop 12 acts as a keeper to secure the handle levers in closed position.

Above the pivot pin 7, the handle levers 5 and 6 are formed into opposed jaws 13 and 14 respectively, the jaw 13 being offset to make the upper ends of the jaws substantially coplanar. The jaws have curved or hook-shaped cable-engaging members 15 and 16 secured to their outer ends, as by welding. As shown, the hook members 15 and 16 are secured to the sides of the jaws and are thus offset from the plane of the jaws.

A swinging arm 17 is mounted at its lower end on the pivot pin 7 and projects upwardly behind the crossed lever portions connected by the pivot pin.

The upper end of the arm 17 carries a bending post 18 which is preferably cylindrical and extends forwardly between and beyond the jaws 13 and 14. The bending post 18 extends forwardly at a right angle to the arm 17 and to the plane of motion of the upper ends of the jaws so as to form a means around which the jaws bend a cable upwardly into a loop as the jaws are brought together from open position of Fig. 3.

As shown, an abutment piece 19 is secured on one of the jaws, shown as jaw 6, and has a curved shoulder 20 which is in the plane of the hooks 15 and 16 for engaging and supporting the closed end of the wire loop 21 as the bending operation is being completed with the wire cable engaged in the hooks.

The inner opposing edges of the jaws 13 and 14 are cut out or recessed a short distance above the pivot pin, as shown at 22 and 23 respectively, to fit around the bending post 18 when the jaws are brought together in the closed position of Fig. 1. In this position, the upper ends of the jaws abut each other and the hooks 15 and 16 are spaced apart. By providing these recesses, the ends of the jaws are kept relatively close to the pivot pin with the result that a maximum amount of leverage is applied through the jaws to effect the bending of the cable.

In the operation of the improved tool, the jaws 55 the spread apart by spreading the handle levers

3

as shown in Fig. 3, and the arm 17 positioned substantially midway between the jaws. A stretch of the cable C which is to be bent into a loop is then positioned between the hook members 15 and 16 and the bending post 18 and the handle levers squeezed together. As the jaws 13 and 14 move toward each other about the pivot 7, the hook members bend the cable upwardly around the bending post in the form of a loop, and as the jaws approach the closed position of Fig. 1, the resilience of the cable C tends to cause the closed end of the loop 21 to spring downwardly where it engages the abutment shoulder 20. When the jaws 13 and 14 reach their closed position, the keeper loop 12 is swung over the lower end of handle lever 10, and a usual clip 25 may be applied to the upper adjacent ends of the loop for securing them together, after which the keeper is released and the tool removed.

Because the jaws 13 and 14 are relatively short, a maximum amount of leverage is applied to the cable on each side of the post 18 at points closely adjacent thereto, so that the cable is bent rather sharply into a relatively small loop. Moreover, the tool is simple and inexpensive to make and easy to operate.

The embodiment of the invention illustrated and described herein is by way of example, and the scope of the invention is not to be limited to exact details of construction.

I claim:

1. A cable looping tool including a pair of crossed handle levers hinged together on a center pivot and having opposed jaws adapted to abut each other in closed position, cable-engaging hooks on the outer ends of said jaws and laterally offset from the plane of the jaws, an arm on

the center pivot carrying a bending post extending between and beyond the jaws at right angles to their plane of motion around which to bend a cable upwardly away from said pivot, an abutment on one of said levers in the plane of the hooks for abutting the lower end of the cable loop as it is bent, and said jaws being recessed to fit around said post when the jaws are closed.

10 2. A cable looping tool including a pair of crossed handle levers hinged together on a center pivot and having opposed jaws adapted to about each other in closed position, cable-engaging hooks on the outer ends of and laterally offset from said jaws, said hooks being spaced apart
15 when the jaws are closed, an arm on the center pivot carrying a bending post extending between and beyond the jaws at right angles to their plane of motion around which to bend a cable upwardly away from said pivot, and an abutment on one
20 of said levers below said pivot for abutting the lower end of the cable loop as it is bent by said hooks.
